UNITED STATES PATENT OFFICE.

JAMES CARVILL GORMAN, OF MANSFIELD, OHIO.

CONVERTIBLE OPEN SPOUT AND PLUNGER FORCE PUMP.

Application filed April 13, 1922. Serial No. 552,263.

To all whom it may concern:

Be it known that I, JAMES CARVILL GORMAN, a citizen of the United States, residing at Mansfield, in the county of Richland and State of Ohio, have invented certain new and useful Improvements in Convertible Open Spout and Plunger Force Pumps; and I do hereby declare the following to be a full, clear, and exact description of the invention, such as will enable others skilled in the art to which it appertains to make and use the same.

This invention relates to pumps, and more particularly to a convertible open spout and closed type diaphragm and plunger force pump.

If a contractor or builder in need of a pump first purchases a pump of the open type as heretofore ordinarily constructed and known as a "lift" pump, which will raise water to a height of about 25 feet, and finds later that the water must be raised to a height of say, 50 feet, it becomes necessary for him to purchase another pump of the closed type, known as a "force" pump, and the cost price of the two separate units is twice or more than twice the cost of a single pump.

The primary object of my invention is to provide a simple, efficient, inexpensive and reliable pump of the open, or closed type with means for easily and quickly converting a pump of the open type into a pump of the closed type, or vice versa, and which will cost little more than one-half of the cost of two pumps—one of the open spout and the other of the closed type—thus enabling the purchaser, for a few dollars in excess of the cost of one pump, to purchase interchangeable parts for converting a diaphragm pump of either the open or closed type into a plunger force pump, or vice versa, and avoiding the trouble and expense incident to the cost of maintenance of two separate units.

A further object of the invention is to produce a pump of the character referred to combining in a unitary structure a pump base or casing with suction valve and superposed jack, crank-shaft and driving gearing, together with interchangeable parts usable therewith for constructing a convertible diaphragm pump of either the open or the closed type, or a plunger force pump, or vice versa.

The invention will first be hereinafter

more particularly described, with reference to the accompanying drawings, which are to be taken as a part of this specification, and then pointed out in the claims at the end of the description.

In said drawings, Fig. 1 represents a vertical longitudinal sectional view of a diaphragm pump of the open spout type adapted for conversion into a diaphragm pump of the closed type, or a plunger force pump;

Fig. 2 represents a vertical longitudinal sectional elevation of the pump structure and operating parts shown in Fig. 1 converted into a plunger force pump;

Fig. 3 is a vertical longitudinal sectional elevation of the pump structure and operating parts shown in Fig. 1 converted into a diaphragm plunger pump of the closed plunger type;

Fig. 4 is a perspective view of a diaphragm pump of the form shown in Fig. 3;

Fig. 5 is a plan view of the pump base and associated parts; the jack and associated parts being removed;

Fig. 6 is a detail vertical sectional view illustrating the mode of securing the legs of the jack and clamping the edges of the diaphragm down upon the pump base; and

Fig. 7 is a fragmentary plan view of the diaphragm clamping ring.

Referring to said drawings, in which the same reference letters are used to denote corresponding parts in different views, the letter A denotes the pump base or casing, which in the form shown has a centrally enlarged portion or water passage and reduced pipe-like extensions a and a' , on opposite sides thereof, forming diametrically opposite inlet and outlet openings, one of which, as a , has inserted and secured therein a valve controlled closure or coupling member B, which is secured to said extension a by means of fastening bolts b^1 inserted through apertured lugs or flanges b on said member B and registering apertures in lugs or flanges a^2 on the free end of said extension a , so as to adapt said coupling member to be readily removed and replaced when desired.

The inner end of said member B is formed or provided with an inclined seat for the inlet valve C, while the outer end thereof is exteriorly screw-threaded for connection with a hose-pipe. The outlet opening in said base is normally closed by a cover-plate D, having apertured lugs or

flanges d to receive fastening bolts d^1 by which it is secured to said pipe-like extension a^1 , said bolts being inserted through registering apertures in radially projecting lugs or flanges a^3 on the free end of said extension a^1 . The pump base or casing A has a central circular opening in its top and an upstanding annular portion or flange A^1 encircling said opening to permit the passage 5 therethrough of a reciprocating plunger operated by driving gearing mounted over said opening as hereinafter described. Said base is also formed or provided with a plurality of radially projecting arms E, having offset 10 end-portions e to which are secured the supporting legs f of a jack F, having mounted thereon suitable bearings in which is journaled a crank-shaft G, which is geared to a countershaft G^1 , which carries at one end 15 fast and loose pulleys over which is passed a belt connecting said pulleys with a power engine or driving means. The legs of the jack are secured to the offset portion e of the lugs E by means of bolts f^1 inserted through 20 registering apertures in said lugs and radially projecting lugs or flanges on the lower ends of the legs of the jack. In the pump shown in Fig. 1 to the crank-shaft G is detachably secured at one end a pitman rod I 25 which has on its free end laterally projecting arms i to which are secured by bolts i^1 clamping rings K and K^1 between which are secured a diaphragm L having a central opening registering with the openings 30 through said clamping rings and also having its outer edge clamped between the upstanding flange A^1 on the pump base and a superposed clamping ring or equivalent device which, in the case of a pump of the 35 open type, may consist of a semi-globular or bell-shaped spout-casing M having an open top and a laterally projecting spout m at one side; said open top being provided with a detachable cover m^1 having a central opening 40 through which the pitman rod I passes. In the case of a pump of the closed type, an ordinary clamping ring may be employed, but preferably a ring of peculiar construction as hereinafter described. The inner 45 rim of the upper clamping ring K forms a valve seat on which a poppet-valve V may rest; said seat being preferably rounded, as shown, said valve having a stem v fitted in a socket in the pitman rod I so that the 50 valve may rise and fall within certain limits independently of the pitman rod. The spout-casing or clamping ring, as the case may be, is mounted on the pump base between the four legs of the jack F, or with- 55 60 65

over the center of said clamping means and the opening in the top of the pump casing with the legs of the jack resting upon radial arms on the pump base exterior to the surface on which the outer edge of the diaphragm rests, so that the diaphragm may be removed without disturbing the plunger operating mechanism. As shown, the radially projecting arms E on the pump base are so formed that the holes therein for the fastening bolts of the spout-casing or other means for clamping the edge of the diaphragm are about $\frac{1}{2}$ inch lower than the holes which receive the anchor bolts for the jack, so as to permit of the machining of 70 that part of the pump base upon which the jack rests without machining the spout-casing or clamping ring; the feet of the legs of the jack being also machined. The described construction permits the plunger or 75 diaphragm and superposed clamping means to be removed without removing or changing the position of the jack, so as to throw it out of alignment, by merely removing the four bolts which hold the spout-casing or 80 the clamping ring in place and the two bolts by which the end of the pitman rod is fastened to the crank-shaft. Another advantage of this construction is that the jack rests on finished metal surfaces, exterior to 85 the support for the spout-casing or clamping ring, and if removed it can only go back into place in its original position, which is not the case with a spout casing or clamping ring resting on a compressible diaphragm. 90 95 100

In Fig. 2 of the drawings is shown a plunger force pump comprising the pump base, jack and plunger operating mechanism shown in Fig. 1, and a solid plunger P having a pitman-rod P^1 pivotally connected at 105 one end with the crank-shaft G, taking the place of the diaphragm and pitman rod and associated parts of the open spout pump shown in Fig. 1, and also having a valve-controlled closure or coupling member R attached to the outlet opening in the pump base and taking the place of the cover-plate D, Fig. 1. Said valve-controlled closure R or coupling member consists of two pipe-like members R^1 and R^2 , one of which, as R^1 , is 110 inserted within the other and secured thereto and to the pump base extension a^1 by fastening bolts inserted in registering apertures in radially projecting lugs or flanges on the two coupling members and said extension a^1 . 115 The part R^1 of the coupling member R is formed or provided with an inclined seat for a discharge valve C^1 and the free end of the part R^2 is threaded for connection with a pipe coupling. The plunger P is slidably 120 fitted within and carried by a cylindrical member or stuffing box S fitting snugly within the circular opening in the top of the pump base and having a laterally projecting portion or flange s adapted to rest upon 125 130

the upstanding flange A^1 of said base. Said member S has secured thereto a gland T , by means of fastening bolts inserted through radially projecting apertured lugs or ears t^1 thereon and similar apertured lugs or ears s^1 on said carrier S , for confining and compressing around said plunger suitable packing material inserted in the space provided therefor between said plunger and the inner 10 wall of said plunger-carrying member so as to provide a water tight joint.

In Fig. 3 of the drawings is shown a diaphragm pump of the closed type taking the place of the diaphragm and associated parts 15 of Fig. 1, in connection with the pump structure shown in Fig. 2 a solid plunger U being secured to a diaphragm, the outer edge of which is clamped between the upstanding flange A^1 of the pump base and a clamping 20 ring O , while its inner edge is clamped between the plunger and a clamping ring O^1 by means of bolts or screws o inserted through holes in said clamping ring and screwed into interiorly threaded sockets in 25 said plunger; said bolts having nuts on their free ends for pressing and holding the clamping ring firmly down upon the diaphragm. The plunger U has secured thereto a pitman-rod I^1 which is pivotally connected 30 at one end with the crank-shaft G . The clamping ring O is preferably constructed in separable parts o^1 and o^2 , of semi-cylindrical form, each part being formed with diametrically opposite overlapping end-portions 35 with registering apertures, one arranged above or below the other flush with the surface thereof, as shown in Figs. 6 and 7 of the drawings, thereby permitting the two parts of the ring to be secured together 40 by bolts O^2 , Fig. 6, which serve also to secure the clamping ring O to the pump body or casing. Said bolts O^2 pass through holes in the arms E of the pump base or casing A which, as shown, project laterally beyond 45 said bolts and have offset portions e provided with bolt holes near their free ends to receive the fastening bolts which pass through apertured lugs on the lower ends of the legs of the jack for securing the jack to the pump 50 casing, as more clearly shown in Fig. 4.

The clamping ring constructed in separable parts and the pump base with radially projecting arms having off-set end portions on which the supporting legs of the jack 55 which carries the driving-shaft and pitman-rod connection with the diaphragm rest and are secured exterior to the surface on which the periphery of the diaphragm or other plunger-carrying means rests, are not 60 claimed herein, and the right is reserved to claim the same in applicant's co-pending applications, Serial No. 384,693 filed May 27, 1920, and Ser. No. 414,859 filed February 14, 1921.

65 The inlet or suction valve C is supported

by a link depending through an opening c in the top of the tubular extension a of the base portion of the pump and pivoted at one end to a lug on the valve and at the other end to a lug on the underside of a cover W for 70 said opening c , said cover being removably attached to the extension a , of the pump base, and in like manner the outlet or discharge valve C^1 is supported by means of a link connecting it with a cover W^1 arranged 75 over an opening in the upper side of the coupling member R at the discharge end of the water passage through the pump base, thus permitting the entire valve assembly at each end of the water passage to be readily 80 removed for repairs, or for the attachment to the pump base extension a^1 of a cover plate or closure D , interchangeably with said coupling member R .

Having thus described my invention, what 85 I claim as new and desire to secure by Letters Patent is:

1. A pump in which a valved or a solid piston are interchangeably used; said pump comprising a hollow base portion having a 90 water passage therethrough, tubular extensions forming inlet and outlet openings at opposite ends of said passage, a central circular opening in its top, and an upstanding flange surrounding said central opening, plunger-carrying means having a circumferential portion resting upon said flange, an inwardly opening valve controlling said inlet opening, a removable closure for said outlet opening and means associated with said base portion for attaching thereto interchangeably with said closure a coupling member carrying a discharge valve, a jack having supporting legs resting on 95 said base exterior to said flange and having a crank-shaft journaled thereon, and a reciprocating plunger supported within said central opening over said passage and having a pitman-rod connection with said crank-shaft.

2. A convertible diaphragm and plunger force pump in which a valved or a solid piston are interchangeably used; said pump comprising a hollow base portion having a 100 water passage therethrough, an inlet opening at one end of said passage, an outlet opening at the other end of said passage, and a central circular opening in its top, said base portion having an integral upstanding flange encircling said central opening and forming a seat for the outer edge of plunger carrying means adapted to rest thereon, a jack having supporting legs secured to said base portion exterior to said 105 upstanding flange and associated parts resting on said flange and also having a crank-shaft journaled thereon, a reciprocating plunger arranged within said central opening and carrying-means therefor supported 110 on said upstanding flange; said plunger 115

having a pitman-rod connection with said crank-shaft; said inlet opening being provided with an inlet valve and said outlet opening having a removable cover-plate secured thereto, said member being adapted for the attachment thereto interchangeably with said cover-plate of a coupling-member carrying a discharge valve.

3. A convertible diaphragm and plunger force pump in which a valved or a solid piston are interchangeably used; said pump comprising a hollow base portion having a water passage therethrough, an inlet opening at one end of said passage, an outlet opening at the other end of said passage, and a circular opening in its top; said inlet opening having secured thereto a coupling-member provided with an inlet valve, and said outlet opening being closed by a removable cover-plate and having means associated therewith for attaching thereto interchangeably with said cover-plate of a coupling-member carrying a discharge valve, a jack mounted on said base portion having a crank-shaft journaled thereon, a reciprocating plunger arranged within said circular opening having a pitman-rod connection with said crank-shaft and associated means secured to said base portion around said circular opening; whereby a pump of the open spout type may be converted into a pump of the closed type; or vice versa.

4. A pump in which a valved or a solid piston are interchangeably used; said pump comprising a hollow base portion having a water passage therethrough, an inlet opening at one end of said passage, an outlet opening at the other end of said passage, a circular opening in its top, and an upstanding flange surrounding said circular opening to provide a seat for the circumferential outer edge of plunger-carrying means seated on said flange, and radially projecting lugs, an inwardly opening valve controlling said inlet opening, a cover-plate removably secured to said outlet opening, the latter opening having means associated therewith for securing thereto interchangeably with said cover-plate a coupling member carrying a discharge valve, a jack mounted on said base portion having a crank-shaft journaled thereon and provided with supporting legs resting on said lugs exterior to said flange, and means for connecting said crank-shaft with a reciprocating plunger arranged within said opening.

5. A convertible diaphragm and plunger force pump in which a valved or a solid piston are interchangeably used; said pump comprising a hollow base portion having a straight water passage therethrough, a central circular opening in its top, an upstanding flange encircling said central opening, and radially projecting lugs exterior to said

flange, and also provided at opposite ends of said passage with tubular extensions forming inlet and outlet openings, a jack mounted over said central opening on supporting legs secured to said lugs, said jack having shaft-bearings thereon and a crank-shaft journaled in said bearings, a cover-plate removably secured to said outlet opening, the latter opening having means associated therewith for attaching thereto interchangeably with said cover-plate of a coupling-member carrying a discharge valve, plunger-carrying means seated on said flange, and a reciprocating plunger arranged within said central opening and having a pitman-rod connection with said crank-shaft, together with means for centering said plunger within said central opening.

6. A convertible diaphragm and plunger force pump comprising a hollow base portion having a water passage therethrough, a central circular opening in its top, and tubular extensions at opposite ends of said passage, one having secured thereto a coupling-member provided with an inlet valve and the other having secured thereto a removable cover-plate, the latter extension having associated therewith means for attaching thereto interchangeably with said cover-plate of a coupling-member carrying a discharge valve, a jack mounted on said base portion over said central opening and carrying a driving-shaft, a reciprocating plunger arranged within said circular opening supported by means resting on said flange and having a pitman-rod connection with said shaft, and means for attaching to said base portion interchangeably plungers of different types arranged within said circular opening and provided with means adapted to rest on said flange for converting a pump of the open spout type into a pump of the closed type, or vice versa.

7. A pump in which a valved or a solid piston are interchangeably used; said pump comprising a hollow base portion having a water passage therethrough, a centrally disposed circular opening in its top, an upstanding flange surrounding said opening, and tubular extensions providing inlet and outlet openings at opposite ends of said passage, in combination with a coupling-member for said inlet opening provided with an inlet valve, a removable cover-plate for said outlet, a diaphragm carrying a reciprocating plunger arranged within said central opening and having its outer edge resting upon said upstanding flange, a spout-casing resting upon the outer edge of said diaphragm and serving to clamp it down upon said flange, a jack mounted on said base portion provided with shaft bearings, a crank-shaft journaled in said bearings, and a pitman-rod connecting said crank-shaft and diaphragm; said base portion having means for

- securing thereto a coupling-member carrying a discharge valve interchangeably with said removable cover-plate, and a solid plunger interchangeably with said diaphragm and arranged within said central opening, said solid plunger having a pitman-rod connection with said crank-shaft, whereby the diaphragm pump may be converted into a plunger force pump, and vice versa.
- 10 8. A convertible pump comprising a hollow base portion having a straight water passage therethrough, tubular extensions providing inlet and outlet openings at opposite ends of said passage, a circular opening in its top arranged centrally over said passage and an upstanding flange surrounding said central opening, said outlet opening having a cover-plate removably secured thereto and said inlet opening having a tubular member inserted therein provided with an inlet valve, the extension for said outlet opening having associated therewith means for attaching thereto interchangeably with said cover-plate a coupling-member carrying a discharge valve, a diaphragm having its outer edge resting on said flange, a spout casing serving to clamp the outer edge of said diaphragm down upon said flange, a jack having supporting legs mounted on said base portion astride said spout casing and having shaft-bearings thereon, a crank-shaft journaled in said bearings, and interchangeable means for securing within said central opening a reciprocating plunger of either the open or closed type having a pitman-rod connection with said crank-shaft, together with means for centering said plunger within said circular opening.
9. A convertible pump in which a valved or a solid piston are interchangeably used; said pump comprising a hollow base portion having a water passage therethrough, a circular opening in its top centrally of said passage, tubular extensions forming inlet and outlet openings at opposite ends of said passage, and an upstanding circular flange surrounding said central opening, a coupling-member secured to said inlet opening provided with an inlet valve, a cover-plate removably secured to said outlet, the latter outlet having associated therewith means for attaching thereto interchangeably with said cover plate a coupling member carrying a discharge valve, a diaphragm having its outer edge resting upon said upstanding flange, a spout-casing resting upon the outer edge of said diaphragm and serving to clamp the same down upon said flange, a jack provided with shaft bearings mounted on said base portion, a crank-shaft journaled in said bearings, and a pitman-rod pivotally secured at one end to said crank-shaft and at the other end to said diaphragm; and a solid plunger interchangeably with said diaphragm, including plunger-carrying means having a circumferential portion adapted to rest upon said flange for supporting the plunger within said central opening, said plunger having a pitman-rod connection with said crank-shaft, for converting a diaphragm pump of the open or closed type into a plunger force pump and vice versa.
10. A convertible pump in which a valved or a solid piston are interchangeably used; said pump comprising a hollow base portion having a straight water passage therethrough, a circular opening in its top with a surrounding upstanding flange, and inlet and outlet openings at opposite ends of said passage, said inlet opening having an inlet valve member inserted therein, and said outlet opening having a cover-plate removably secured thereto and having associated therewith means for attaching thereto interchangeably with said cover-plate a coupling-member carrying a discharge valve, a diaphragm having its outer edge resting on said flange, a removable spout casing serving to clamp said outer edge of said diaphragm down upon said flange, a jack having supporting legs mounted on said base portion exterior to said diaphragm and astride said spout casing and having shaft bearings thereon, and a crank-shaft journaled in said bearings, said base portion having associated therewith means for attaching thereto within said circular opening, a solid plunger with supporting means resting upon said flange and having a pitman-rod connection with said crank-shaft, for converting a diaphragm pump into a plunger force pump or vice versa.
11. A convertible pump in which a valved or a solid piston are interchangeably used; said pump comprising a base portion having a water passage therethrough and integral tubular extensions of said passage at opposite ends thereof provided with terminal apertured flanges adapted for attaching to one of said extensions an inlet-valve member and to the other extension a discharge-valve member interchangeably with a removable cover-plate; said base portion also having a circular opening through its top and an upstanding annular flange surrounding said opening and radially projecting apertured lugs; said flange providing a seat for the outer circumferential edge of means for supporting a reciprocating plunger within said circular opening, a jack mounted on said base having supporting legs secured to said apertured lugs exterior to said flange; said jack having a driving shaft journaled thereon, and means for securing to said base interchangeably a diaphragm or other plunger-carrying means with a plunger having a pitman-rod connection with said driving shaft.
12. A pump in which a valved or a solid

piston are interchangeably used; said pump comprising a base portion consisting of a hollow body having a straight water passage therethrough and integral tubular extensions provided with apertured end flanges at opposite ends of said passage, fastening bolts in said flanges, an inlet-valve member attached by certain of such bolts to the flange at one end of said body, and a 10 discharge valve member attached by other of such bolts to the flange at the other end of said body, a cover plate for closing the discharge end of said passage, said cover plate being interchangeable with said discharge valve member; said base portion also having a circular opening through its top and an upstanding flange surrounding said circular opening and radially projecting apertured lugs on said flanges, a jack mounted on said base having legs attached to said lugs, a driving shaft carried by said jack, a plunger supported within said circular opening, a pitman rod connection between said shaft and plunger, and plunger carrying 20 means having a circumferential portion adapted to rest upon said flange.

13. A pump in which a valved or a solid piston are interchangeably used; said pump

comprising a base portion having a central circular opening in its top and inlet and outlet openings on opposite sides thereof, and integral laterally projecting lugs on opposite sides of said inlet and outlet openings, combined with a jack having depending legs secured to said lugs, a crank shaft carried 30 by said jack, plunger-carrying means adapted to be supported within said central opening, a plunger and a pitman rod connection between said plunger and shaft, said base also having a flange surrounding said 35 central opening and forming a rest for a circumferential portion of said plunger-carrying means, and means for attaching to said inlet opening an inlet valve and to said outlet opening a removable closure plate interchangeably with a removable discharge valve, whereby the pump may be converted at will from a plunger force-pump to a diaphragm pump of either the closed or open type and vice versa. 45

In testimony whereof I affix my signature in the presence of two witnesses.

JAMES CARVILL GORMAN.
